United States Patent Office

Des. 205,333

Patented July 19, 1966

205,333

SATCHEL OR THE LIKE

Dona G. Cain, 2564 N. Fleetwood Drive, Mobile, Ala.

Filed Mar. 29, 1965, Ser. No. 84,498

Term of patent 14 years

(Cl. D87—3)

I claim:

The ornamental design for a satchel or the like, as shown.
